[57] **CLAIM**

The ornamental design for a combined whistle and cricket noise maker for use as a divers signal above and below the water surface, substantially as shown and described.

DESCRIPTION

FIG. 1 is a view of the mouthpiece end and one side of the combined whistle and cricket noise maker for use as a divers signal above and below the water surface embodying our design;

FIG. 2 is an end view of the signaling device of FIG. 1;

FIG. 3 is a side view of the signaling device;

FIG. 4 is a top view of the signaling device;

FIG. 5 is a view of the opposite end from FIG. 2; and

FIG. 6 is a bottom view of the signaling device.

FIG. 1

FIG. 2

FIG. 3

FIG. 4

FIG. 5
